United States Patent Office.

JOHN BACHELDER, OF NORWICH, CONNECTICUT.

Letters Patent No. 65,328, dated June 4, 1867.

IMPROVEMENT IN SELF-LUBRICATOR.

The Schedule referred to in these Letters Patent and making part of the same.

TO WHOM IT MAY CONCERN:

Be it known that I, JOHN BACHELDER, of Norwich, in the county of New London, and State of Connecticut, have invented a new and improved Mechanical Device for Applying Oil or other Liquid Substances for Lubricating Bearings of Shafting and Machinery.

The nature of my invention consists in returning the lubricator after being strained to the shaft or journals continuously; and I do hereby declare that the following is a full and exact description of the construction and operation of the same, reference being had to the accompanying drawings, making a part of this specification, in which—

Figure 1 is a front elevation with intervening supporting columns removed.

Figure 2, a longitudinal section parted vertically through the centre of the shaft; and

Figure 3 a transverse section.

In these figures, *a* represents a shaft supported in hangers *b*. *c* represents a circular metallic plate, with a concave surface inclining towards the bearing, secured to and revolving with the shaft to be lubricated. The diameter of this plate *c* is determined by the speed of the shaft on which it is set, that in the model being calculated for about five hundred revolutions per minute. It is more readily applied to shafting by being made in halves. *d* represents a conductor for the purpose of transferring the oil thrown off by centrifugal force from the periphery of the plate *c* to the cavity in the cap of the hanger *b*. This conductor may be made of metal, wood, or a string secured in the proper position. *e* represents a thin vertical plate-flange, secured to or cast on the hub of the larger plate *c* to intercept the oil flowing from the plate *c*, and return it to the dripping-pan or fountain *f*. The bar *g*, the top of which is made of perforated sheet metal or wire cloth, is set in the bottom, near one end of the dripping-pan *f*, and prevents the sediment and scum in and upon the returned oil from flowing into the end where the plate *c* is revolving in strained oil. *i* represents a cap or hood covering the plate *c*, intercepting the oil thrown off by it and supporting the conductor *d*. In mills where much lint or dust is floating in the atmosphere, the hood is made to cover the whole bearing. That in the model is made narrow, and open, the better to show its operation.

In order to show the operation and effect of my invention, I have placed a pulley, *h*, on the shaft *a*. When the shaft is driven at the requisite speed, the periphery of the plate *c* running in clean oil placed in the dripping-pan *f*, carries it up by centrifugal force above and into the conductor *d*, which delivers it in the cavity in the cap of the hanger *b*. The oil then, after performing its office of lubricating, passes out at the ends of the bearing in the usual way, or may pass through a hole under the shaft into the larger part of the dripping-pan. The sediment then settles and the lighter portion of the oil passes through the strainer on the top of the bar *g* to be again taken up and returned as before, using the same oil continuously and straining it as it is returned.

What I claim as my invention, and desire to secure by Letters Patent, is—

1. The revolving plate *c*, the conductor *d*, the vertical flange *e*, the hood *i*, and the arrangement of the bar and strainer *g* in the dripping-pan.
2. The combination of the revolving plate *c* and the conductor *d*, or its equivalent, all for the purposes herein described.

JOHN BACHELDER.
